POTENTIAL RECORDING MECHANISM

Franklin Offner, Chicago, Ill.

Application February 17, 1939, Serial No. 257,005

3 Claims. (Cl. 234—5.5)

This invention relates to improvements in electric potential recorders and particularly to improvements in direct recording electrocardiographs.

An object of the present invention is to provide for more faithful recording at higher frequencies and with larger amplitudes than has previously been possible.

Another object of the invention is to provide a novel form of coupling between the piezo-electric crystal elements and the recording element.

Other objects and advantages of the invention will be evident from the following description taken in conjunction with the accompanying drawings which illustrate a preferred embodiment of the invention.

In the drawings:

Fig. 1 is a top plan view of the recording mechanism forming a part of the invention.

Fig. 2 is a front elevation thereof.

Fig. 3 is an enlarged sectional view taken on the line 3—3 of Fig. 1.

Fig. 4 is an enlarged view of the crystal container with the front plate removed.

Fig. 5 is a sectional view taken on the line 5—5 of Fig. 4.

Fig. 6 is a diagrammatic illustration of an electrocardiograph recording system embodying the invention, and

Fig. 7 is an illustration of a calibration record produced by the invention.

The recording mechanism shown in Figs. 1 to 5 is mounted on a cabinet 10, the top of which is formed of a metal plate 11 which forms a base for mounting the various elements of the recorder.

The recording pen assembly is mounted on the front cover plate 12 of an upstanding casing 13. The casing 13 is pivoted at one end thereof on a horizontal stub shaft 14 carried by a block 15 mounted on the plate 11. A bored block 16 secured to the side of the casing by screws 17 slides on the shaft 14 to effect the pivotal mounting. A locking set screw 18 secures the casing in axially adjusted position on the shaft 14. The other end of the casing 13 rests on an adjustable stop in the form of a set screw 19 threaded into the plate 11 which provides a means for adjusting the elevation of the casing and thus the contact pressure of the recording point on the record tape.

The recording pen arm 20 is actuated by a pair of piezo-electric crystal bending units 21 and 22 mounted in substantially the same plane within the casing 13 with the driving points 55

thereof adjacent each other. The piezo-electric crystal units 21 and 22 are preferably of the type disclosed in the patent to Alfred L. Williams No. 2,105,011 dated January 11, 1938, and are provided at each of three corners with metal bearing plates 23 on the front face thereof which bearing plates are formed to provide ball-like protuberances or pivot bearings 24. These pivot bearings contact the inner face of the cover plate 12 of the casing 13 and are held firmly in contact therewith by resilient rubber blocks 25 disposed between the rear wall of the casing and each of the said three corners of the crystals which are provided with bearing plates 23. A thin layer of rubber 26 is disposed between each of the bearing plates 23 and the surface of the crystal elements. When the crystals are disposed in the casing as shown in Figs. 4 and 5 and the cover plate 12 is applied and the screws 27 which secure the cover plate in position, are tightened, the crystal units are firmly supported between the cover plate and the rear wall of the casing, being clamped between the bearing plates 23 and the rubber blocks 25.

With three corners of each of the rectangular crystal elements 21 and 22 clamped as described above, the free corners 28 and 29 respectively, which are disposed adjacent each other are free to move in response to any piezo-electric deformation in the crystal units produced by the application of electrical potential thereto. The fourth and movable corners of the crystal units are provided with metal clips 30 and 31, respectively, which engage over the corners and are cemented in position. Each of the clips or corner pieces 30 and 31 carries a phosphor bronze strip in the form of a projecting arm disposed at right angles to the face of the crystals. These arms, designated 32 and 33, respectively, have the inner ends rigidly secured to the respective clips 30 and 31. The arms 32 and 33 are parallel to each other and extend forwardly through a suitable opening 34 in the cover plate 12 of the casing 13 for transmitting the motion of the crystals to the external mechanical system to be presently described.

The electrical connections to the crystal units are made through tin foil plates in the manner described in the aforementioned patent to Williams and the two crystal units are electrically connected in parallel but in such sense that when an E. M. F. is applied, the free corners 28 and 29 thereof move in opposite sense so that the arms 32 and 33 move along substantially parallel paths in opposite directions.

Because of the relatively small deformation of the crystal units themselves and the correspondingly slight movement of the arms 32 and 33 carried by the movable corners thereof, it is necessary to provide for a large mechanical multiplication of this motion. In order to effect this multiplication of the crystal motion, the forward ends of the arms 32 and 33 are connected to opposite sides of a rocking member in the form of a small pulley element 35 which is formed with, or rigidly connected with, a coaxial larger pulley segment 36. The ends of the arms 32 and 33 are preferably soldered to opposite sides of the pulley 35 as indicated at 37 and 38. The diameter of the small pulley 35 is preferably about $\frac{1}{4}$ inch and that of the large pulley segment about $1\frac{1}{4}$ inches. The dual pulley 35-36 is carried on a pivot shaft 39 which is journalled in jewel bearings 40 and 41 mounted in a supporting block 42 rigidly secured to the face of the cover plate 12.

The supporting arm 20 for the marking element is carried on a pivot shaft 43 the pointed hardened ends of which are journalled in cup jewel bearings 44 and 45 mounted in the opposed ends of screw members 46 and 47 adjustable in the projecting arms of brackets 48 and 49 secured to the upper and lower faces of a block 50 which is adjustably mounted on forwardly projecting pins 51 carried by the block 42. A pair of locking and adjusting screws 52 and 53 are provided for adjusting the position of the block 50 on the pins 51. The screw 52 extends through a smooth bore in the block 50 and is threaded in a socket in the block 42 so that tightening of the screw 52 tends to draw the block 50 up to the block 42. The screw 53 is threaded through the block 50 and its inner end bears against the surface of block 42 so that tightening the screw 53 tends to force the blocks 42 and 50 apart. By relative adjustment of the screws, the position of the block 50 can be adjusted and locked due to the opposing forces exerted by the screws.

The pivot shaft 43 is parallel to the pivot shaft 39 carrying the pulleys 35 and 36 and is provided with a small pulley 54 in horizontal alignment with the pulley segment 36. A very thin brass band 55 having its opposite ends fastened to the pulley segment 36, as by small hooks 56 and 57 mounted at the ends thereof, is trained around the pulley 54 on the pivot shaft 43 for the purpose of transmitting motion of the pulley segment to the shaft 43. The diameter of the pulley 54 is preferably about $\frac{1}{4}$ inch. By adjusting the screws 52 and 53 the block 50 may be disposed and locked in position to adjust the tension of the pulley band 55.

The supporting arm 20 for the marking element 58 is preferably made from a duralumin stamping about .002 of an inch thick and carries a small ink tube 59 connected to the writing point 58 mounted at the end thereof. Ink is carried to this assembly through a fine rubber tube 60 from an ink well 61 carried on a post 62 and adjustable in height to vary the ink pressure supplied to the writing point.

Since the crystal elements may be affected by moisture, it is desirable that the container 13 be tightly sealed. To effect this, a flexible rubber diaphragm 63 (Fig. 3) is mounted across the opening 34 in the cover plate 12 and the motion transmitting arms 32 and 33 project through this diaphragm, being sealed thereto by rubber cement. A suitable gasket 64 is also disposed be-

tween the cover plate 12 and the walls of the casing 13 to provide a seal at this joint.

It has been found that the use of two crystalline elements connected to move in opposite sense as above described possesses several advantages. First it provides double the power of a single element which allows the amplitude of motion of the marking element to be increased by the factor the square root of two, while maintaining the same frequency response, or allows the frequency response to be increased by the same factor while maintaining the same available amplitude. Also, due to the connections employed where the amplitude of motion of each crystal element is exactly the same, a pure torque is supplied to pulley 35 and pulley segment 36 so that in theory, the shaft and bearings for these pulley elements could be dispensed with entirely, and in actual practice some slight play in these bearings will not result in any lost motion in the system. Great care in avoidance of any possibility of lost motion in any portion of the mechanical system is particularly important in a piezo-electric crystal actuated recording system of this type because the motion of the crystals themselves is so minute as compared with the final resultant motion of the marking point. Thus a lost motion of .001 inch between the crystals and the segment due to play in the segment bearings would result in lost motion of 0.1 inch at the marking point, assuming a ratio of 100 to 1, a representative value. It will be noted that with the mechanical system herein disclosed, all parts of the system are under tension and thus no lost motion can occur in any part thereof.

The traveling tape 65 for receiving the record is served from a roll 66 mounted within the cabinet 10, passing over tensioning guide rods 67, through a slot 68 in the base plate 11 and thence over the surface of the plate between upper and lower feed rolls 69 and 70, respectively. The upper tape feeding roller 69 is mounted on a shaft 71 journalled in bearings 72 mounted on the plate 11 while the lower roller 70 is mounted on a shaft 73 journalled between the free ends of spaced arms 74, the other ends of which are pivoted on a bracket 75 on the underside of the plate 11. Tension adjusting screws 76, threaded into the respective arms 74 adjacent their free ends extend through openings 77 in the plate 11 and have springs 78 confined between the heads of the screws and the surface of the plate. Tightening or loosening the screws 76 results in varying the pressure between the rollers 69 and 70.

The tape feeding roller 69 is driven by a synchronous motor 79 through a variable speed drive. The motor 79 is provided with a built on reduction gear drive 80 on the output shaft 81 of which gears 82 and 83 are mounted. The gear 82 is the larger of the two and is adapted to mesh with a smaller gear 84 on the shaft 71 of roller 69 while the gear 83 is smaller and is adapted to mesh with a larger gear 85 also mounted on shaft 71, as shown in Fig. 1.

In order to provide for shifting the gears 82 and 83 selectively to engage them with the respective gears 84 and 85, the motor 79 is mounted on parallel links 86 and 87, pivoted at one end on the plate 11 as indicated at 88 and having pivotal connection to the motor base as indicated at 89. The link 87 extends beyond the edge of the plate 11 to provide a handle 90 which serves for swinging the linkage mechanism to shift the motor and gear assembly including the

gears 82 and 83 so that either one of the latter may be engaged selectively with its associated gear 84 or 85.

The electrical circuit connections for use of this potential recording marker in electrocardiography are shown in Figure 6. Here 90 represents the writing mechanism described above, 91 a thermionic vacuum tube amplifier, and 92 a variable series resistance element placed in series between 90 and 91. A series of switches 93, 94, 95 and 96 are used to connect the proper pairs of patient electrodes from the four standard electrical lead positions, right arm, left arm, chest and left leg, to the amplifier input terminals. These patient electrodes are numbered 97, 98, 99 and 100, respectively.

A calibrating means 101 is interposed in series with the amplifier input. This is so arranged that direct potential pulses of 1 millivolt amplitude or an alternating potential of 1 millivolt peak amplitude may be alternatively introduced.

One way of constructing such a calibrating means is indicated in Fig. 6. A resistor 102 is interposed in series with the input of the amplifier and either a direct current or an alternating current may alternatively be passed through this resistor by throwing switch 103. The D. C. is obtained from battery 104 and the current as read on meter 114 is adjusted by variable resistor 105 so that its value is sufficient to give the proper voltage drop in resistor 102. The A. C. is obtained from transformer 106, the primary of which is connected to a 60 cycle A. C. supply line. A grounded electrostatic shield 107 is interposed between the primary and secondary. Here again the current which is passed through resistor 102 is adjusted to the proper value as read on meter 115, by a variable resistor 108. Now when switch 103 is rapidly opened and closed in the down position a series of D. C. pulses is applied to the amplifier input, while throwing the switch in the up position will apply an alternating current. The function of this will be discussed later.

The amplifier is preferably of the resistance capacity coupled type having a variable voltage gain of up to about three hundred thousand times and an overall time constant of approximately one to two seconds. It should be capable of delivering a peak output voltage of about six hundred volts and its output impedance should be under approximately forty thousand ohms. The purpose of the variable series resistance element 92 is to provide damping of the motion of the recorder. The leads 109 and 110 from the amplifier may be connected to the crystals through binding posts 111 and 112.

Damping is required in this recorder because the moving mechanical system attached to the crystals has such relatively large inertial effect it will reduce the resonant frequency of the system composed of the crystals and mechanical system to a frequency approaching that which it is desired to record. Although this moving system be made as light as practicable, such an inertial effect will still be produced, for the amplitude of motion of portions of the system, and especially of member 28 and associated marking element and ink tube, is relatively very great as compared with the motion of the crystals. The effective inertia of any portion of the system is found by multiplying its actual mass by the square of its amplitude of motion; and thus it is seen that the mass of the marking element may be 100^2 or 10,000 times as important as an

equal mass at the driving point of the crystal itself. The total inertial effect of the moving mechanical system in the instrument as here described, is such that the mass of the crystals themselves is negligible in comparison therewith.

Now assuming that there were no damping introduced in the electro-mechanical system, as the resonant frequency is approached the amplitude of motion produced by a constant input voltage would greatly increase, and thus give distorted records of wave form. However, by properly introducing damping means, either electrical or mechanical, it is possible to dissipate relatively more power in such means as the resonant frequency is approached, and by careful adjustment of this means a relatively uniform response amplitude may be obtained, independent of frequency, even up to frequencies slightly surpassing the first electro-mechanical resonant frequency of the system. As previously disclosed, it is possible to obtain such damping by the use of such a series resistance, and applicant has found that in the present invention is is desirable to obtain damping of the motion by this means in preference to mechanical damping. Applicant has found that the optimum value of this resistance may be very simply found by the use of calibrator 101. A direct potential of 1 millivolt is introduced and the response amplitude adjusted to a suitable value (e. g. 1 cm. as standard for electrocardiography) by varying the amplifier gain. Now an alternating potential of this same peak amplitude is introduced and the damping resistor 92 is adjusted until the response amplitude obtained from the alternating potentials is equal to that obtained with the direct potential. The appearance of records when properly damped is shown in Fig. 7. Here 116 represents the form of tracing which would be obtained with the direct current pulses and 117 that obtained with the alternating current. The frequency of alternating current to be here used is not critical but should lay in the middle range of the instrument. 60 cycles per second is a suitable value. The justification for this method of damping is as follows: The most desirable form of frequency response for a recorder is one in which all frequencies are recorded with equal amplitude (assuming they are of the same voltage). Applicant has found that if direct current pulses (in effect very low frequencies) and medium frequency potentials (as here 60 cycles per second) are recorded with the same amplitude the frequency response curve of the instrument is made as nearly flat as possible. A variation of the damping resistor 92 will not affect appreciably the amplitude of the direct current pulses because of the relatively high impedance of the recorder to direct current, and thus the calibration need not be reset after adjusting the damping control. Although the voltages supplied for adjusting the damping are here shown in series with the input they may be alternatively inserted in any positions in the system so long as they introduce equal voltages in series with the output impedance of the amplifier.

In operation, calibration and other adjustments may be performed with switch 118 closed, shortcircuiting the patient circuit. After these adjustments are completed, switch 118 may be opened. The patient electrodes are applied to the body in the four positions indicated, and a pair of the switches 68-69 are closed to connect a selected pair of electrodes to the input

terminals of the amplifier. The recording point will mark a direct record of the wave form of the body potentials as modified by the heart action so as to produce a cardiogram suitable for diagnosing the condition of the heart. Calibration may also be performed with the patient in the circuit, with switch 118 open.

Although a preferred embodiment of the invention and manner of employing the same have been illustrated and described by way of example, it will be understood that various modifications of the details of construction and mode of operation may be resorted to without departing from the spirit of the invention within the scope of the appended claims.

I claim:

1. In a potential recording mechanism of the character described, a pair of piezo-electric crystalline elements supported with the driving points thereof adjacent each other and connected to a current source in such manner that said driving points move in opposite directions under the influence of an applied electric field, each of said points carrying a relatively stiff arm rigidly connected thereto and projecting therefrom in a direction substantially normal to the face of said units, a rocking member spaced from said driving points, said arms being rigidly connected to said rocking member at opposite sides of the axis thereof to provide a two-way drive between each of said crystals and said rocking member, a pivoted recording arm, and tensioned driving connections between said rocking member and said recording arm.

2. In a device for making legible marked records of the wave form of varying electrical potentials, a pair of piezo-electric crystal units supported with the free ends thereof adjacent and connected with the current source in reverse relation so as to respond in opposite sense under the influence of applied electrical potential, a pivoted rocking member, two-way motion transmitting connections from the free ends of said crystal units to points on opposite sides of the

axis of said rocking member, said connections each comprising a relatively stiff link rigidly fastened at one end to one of said driving points and rigidly fastened at its other end to said rocking member, a pivot shaft spaced from the axis of said rocking member and substantially parallel thereto, a small diameter pulley member on said pivot shaft, a flexible band providing a driving connection between said rocking member and said pulley member, a recording arm carried by said pivot shaft and a marking element adjacent the free end of said arm.

3. In a device for making direct legible marked records of the wave form of varying electrical potentials, a plurality of piezo-electric crystal elements connected in reverse parallel relation with the source of said potentials, and having movable portions adjacent each other, a pivoted recording arm, motion multiplying means providing a driving connection between said crystal elements and said recording arm, said driving connection comprising a rocking unit including a pair of coaxial rocking pulley members of different diameters, a relatively stiff projecting arm rigidly secured at one end thereof to the movable portion of each of said crystal elements, said arms being rigidly connected at the other end thereof to the pulley member of smaller diameter on opposite sides of the axis thereof to provide a positive two-way drive connection between the movable portion of each crystal element and the rocking unit whereby said crystal elements mutually aid each other in imparting a rocking action without lost motion to said pulley members, a pivot shaft for said recording arm disposed substantially parallel with the axis of said pulley members, a pulley member carried by said pivot shaft having a diameter less than that of the larger of said first mentioned pulley members, and a flexible driving connection between the peripheries of the larger of said first mentioned pulley members and the pulley on said pivot shaft.

FRANKLIN OFFNER.
